UNITED STATES PATENT OFFICE

2,008,422

OSCILLATORY MOTOR

George H. Leland, Dayton, Ohio, assignor of one-half to The Leland Electric Company, a corporation of Ohio

Application March 20, 1931. Serial No. 524,195

21 Claims. (Cl. 172—126)

This invention relates to automatic circuit breakers and closers and is designed more particularly for intermittently opening and closing one or more lamp circuits. Automatic switches of the mercury tube type have been used heretofore for controlling lamp circuits but in a switch of this kind it is necessary that some means be provided for so retarding or regulating the movement of the circuit breaker and closer as to provide a relatively slow and uniform movement thereof. The devices used for this purpose have not been entirely satisfactory and in the application for patent filed by me November 10, 1930, Serial No. 494,570 I illustrated and described an automatic circuit breaker and closer which overcomes the objections to the earlier devices and the present application covers a further development of the invention of that application.

25 A further object of the invention is to provide a circuit breaker and closer of this type in which the circuit breaking and closing element will be moved in one direction by gravity and in the other direction by an electrically operated device and in which the movement of the circuit breaker and closer element will be controlled or regulated by an inertia element which is separate from the electrically operated device.

30

A further object of the invention is to provide such a circuit breaker and closer which is simple in its construction and which is of such a character that it will maintain a uniform timing of the circuits indefinitely.

Other objects of the invention will appear as the apparatus is described in detail.

40 In the accompanying drawings Fig. 1 is a top plan view of an automatic circuit breaker and closer embodying my invention; Fig. 2 is a front elevation of the same; Fig. 3 is a section taken on the line 3—3 of Fig. 2; Fig. 4 is a rear elevation of the apparatus; Fig. 5 is a section taken on the line 5—5 of Fig. 1; Fig. 6 is a section taken on the line 6—6 of Fig. 2; Fig. 7 is a detail of the frictional connection between the switch supporting member and the magnet armature; and Fig. 8 is a circuit diagram.

In these drawings I have illustrated one embodiment of my invention and it will be understood that this has been chosen for the purposes of illustration only and that the apparatus may take various forms without departing from the spirit of the invention.

In that embodiment here illustrated the several parts of the mechanism are mounted on a supporting frame comprising a back plate 1, which is mounted in a vertical position. The cir-

cuit breaking and closing element is preferably in the form of a mercury tube switch, as shown at 2, and this switch is mounted in clips 3 carried by a supporting member 4. The supporting member is so arranged that it will be moved by gravity in one direction and it is here shown as an elongated arm pivotally mounted at one end on a stud 5 mounted in the back plate 1. Preferably the supporting arm is rigidly secured to a sleeve 6 which is rotatably mounted on the stud. The supporting member and the circuit breaker and closer carried thereby are moved in the opposite direction, that is, against the action of gravity, by an electrically operated device which is here shown as an electro-magnet 7 mounted on the frame 1 and having depending pole pieces 8 between which is arranged a Z-shaped armature 9. This armature preferably has its axis coincident with the axis of the pivoted supporting member and, as here shown, it is rigidly secured to the sleeve 6 which carries the supporting member. Preferably a power absorbing device is provided to gradually check the movement of the armature and supporting member at the end of each oscillation, and, in the present instance, I have inserted a friction member between these parts. As here shown, the friction member is in the form of a plate 10, preferably of fiber, which is mounted for movement about the axis of the armature and which extends laterally therefrom and has its free end recessed, as shown at 11, to receive a fixed stud 12. The length of the recess is such that the ends thereof will engage the stud and interrupt the movement of the plate before the armature and supporting member have completed their movement in either direction. Connected with the supporting member 4 is a friction element 13 which bears against the plate 10 and forces the latter against the end of the armature with sufficient force to cause the plate to move with the armature and supporting member but which will permit a continued movement of the armature and supporting member against frictional resistance after the movement of the plate has been interrupted. In the present device, the supporting arm 4 extends some distance beyond its axis and the friction member 13 is in the form of an elongated plate which is connected with the supporting arm for movement therewith and has a curved or bowed portion to exert pressure on the plate 10. A set screw 14 serves to adjust the pressure of the member 13 on the plate 10.

Connected with the supporting member 4, preferably at the free end thereof, is an inertia element, which is here shown as a rotary disk 15 carried by a shaft 17 rotatably mounted in bearings 18 and 19 supported on the main frame. Connected with the shaft 17 is a pinion 20 which may, if desired, be formed integral with the shaft 17.

and which meshes with a toothed rack 21 carried by and forming a part of the supporting member and preferably arranged adjacent to the free end thereof. It will be apparent that the connection between the supporting member and the inertia element is such that these two members will move in unison and that the movement of the supporting member, either by gravity or by the electrically operated device, will be regulated by the inertia element.

I have also provided means for cushioning the reversal of the movement of the supporting member. This cushioning means is substantially identical with that shown and described in the above mentioned application and, briefly, it comprises an arm 22 secured to the sleeve 6 near the back plate 1, and having adjustably mounted thereon a finger 23, which extends through a tapered opening 24 in the back plate and is arranged between the upper and lower stretches of an endless resilient band 25 which is mounted on the rear surface of the back plate. This finger will contact with one or the other of the stretches of the yieldable band as the supporting member approaches the limit of its movement in either direction, thus yieldably checking that movement. The contraction of the band, after it has been engaged by the finger, will tend to impart a reverse movement to the finger and to the supporting member and thus facilitate the initial movement of the supporting member in the opposite direction. The tapered or converging edges of the opening 24 constitute stops to positively limit the movement of the finger and of the supporting member at fixed points. The finger may be adjusted lengthwise of the arm 22 and the angular arrangement of the fixed stops, or edges of the opening, is such that in any adjustment of the finger on the arm the arm will move the same distance and will occupy the same angular position when the finger engages the fixed stop. When the finger is positioned near that end of the arm remote from the axis the finger will engage the yieldable band earlier in the movement of the arm than it will when the finger is close to the axis of the arm and the band will be placed under greater tension with the result that it will impart a quick return movement to the arm, thus speeding up the action of the switch. The positive stops are not necessary to the operation of the device and are used only to prevent the segment being moved out of mesh with the pinion.

The electrically operated device 7 is so connected with the circuit breaking and closing element 2 that when the supporting member and circuit breaking and closing element approach the lower limit of their movement by gravity the circuit will be closed and the electrically operated device energized to impart movement to the supporting member in the opposite direction. As the supporting member approaches the limit of its movement in this opposite direction the circuit will be broken to deenergize the electrically operated device and release the supporting member therefrom. In the present device, the circuit breaking and closing element, or mercury tube switch has three contacts 26, 27 and 28 which are so arranged that when the tube is tilted in one direction the mercury therein will connect the contacts 27 and 28 and when the tube is tilted in the other direction the mercury will connect the contacts 26 and 27. Referring to Figs. 2 and 8 of the drawings it will be noted that the terminal or contact 27 of the mercury tube is connected by a conductor 29 with a terminal 30

which in turn is connected to one side, 31, of the power line. The contact 28 at one end of the tube is connected by a conductor 32 with a terminal 33, which terminal is connected by a conductor 34 with one end of the coil of the electro-magnet 7. The other end of the magnet coil is connected by a conductor 35 with a terminal 36 which is connected by a branch 37 to the other side, 38, in the power line. The terminal 33 is also connected by a conductor 39 with a lamp 10 or group of lamps, as shown at 40, which lamp is connected with the line 38. The other end contact or terminal of the mercury tube, 26, is connected by a conductor 41 with a terminal 42 which is connected by a conductor 43 with a second lamp or group of lamps, as shown at 44, and this second lamp is also connected with the conductor 38. It will be apparent therefore that when the mercury tube is in the position shown in Fig. 2 the circuit will be closed through both the electrically operated device or magnet and through the first lamp 40. When the mercury tube is tilted in the other direction the circuit will be broken through the electrically operated device or magnet and through the lamp 40 and will be closed through the second lamp or group of lamps 44. This arrangement closes the circuits through the two lamps alternately and if it is desired merely to make and break the circuit through one lamp the connection with the contact 26 may be eliminated or a two-contact tube may be employed. It will be obvious that the tube may take any suitable form but, in the present arrangement, I prefer to use the curved three-contact tube.

When the mercury tube switch is inclined in the direction shown in Figs. 2 and 8 the circuit will be closed through the electrically operated device and upward movement will be imparted to the tube, thus tilting the same in the opposite direction. This tilting movement will result in the breaking of the circuit through the electrically operated device before the tube has completed its movement and the inertia member will then function to assist in the completion of the movement of the tube and its supporting member. When the upward movement has been completed, and checked by the cushioning device, the tube and its supporting member will move downward by gravity but in so doing must overcome the inertia of the inertia element 16 and the action of this inertia element will cause the tube to move downward at a relatively slow and uniform speed. The tube will be tilted toward its first mentioned position sufficient to again close the circuit through the electrically operated device before the tube completes its downward movement but due to the action of the inertia element the downward movement of the tube will be continued against the action of the electrically operated device, which will then function as a brake to retard the further movement of the tube. After the downward movement of the tube has been stopped the electrically operated device must overcome the inertia of the inertia element before the tube can begin its upward movement, thus preventing the sudden starting or jerking of the tube. Due to the lag of the mercury in the curved tube the angular position to which the tube must be moved to open the circuit is substantially higher than the position to which it must be moved to close the same. Consequently the electrically operated device or motor will not begin to function until the tube has completed the major portion of its downward movement and will then continue

- to function until the tube has completed the major portion of its upward movement. By varying the power exerted on the supporting member to impart return or downward movement thereto, with relation to the power of the electrically operated device, the timing of the switch may be varied, that is, the circuit may be retained closed for a longer or shorter period of time with relation to the period that it remains open. In the present device, I have provided the supporting member 4 with an adjustable weight 45 which serves not only to increase the gravitational action of the support and the tube but may be adjusted lengthwise of the support to vary the gravitational power thereof.
- While I have shown and described one embodiment of my invention I wish it to be understood that I do not desire to be limited to the details thereof as various modifications may occur to a person skilled in the art.
- Having now fully described my invention, what I claim as new and desire to secure by Letters Patent, is:
1. In a device of the character described, a pivoted supporting member, a circuit breaker and closer carried by said supporting member, an inertia element connected with said supporting member, an electrically operated device connected with said supporting member, power absorbing means for gradually checking the movement of said armature and said supporting member at the end of each movement thereof, and electrical connections between said circuit breaker and closer and said electrically operated device to cause the latter to be operated when said supporting member is moved in one direction and to cause the operation thereof to be interrupted when said supporting member is moved in the other direction.
  2. In a device of the character described, a pivoted supporting member, a circuit breaker and closer carried by said supporting member, an inertia element connected with said supporting member, an electro-magnet having its armature connected with said supporting member, a retarding device yieldably connected with said supporting member for movement therewith, means for interrupting the movement of said retarding device before said supporting member has completed its movement, and electrical connections between said circuit breaker and closer and said electro-magnet to cause the latter to be energized when said supporting member is moved in one direction and to be deenergized when said supporting member is moved in the other direction.
  3. In a device of the character described, a pivoted supporting member, a circuit breaker and closer carried by said supporting member, an inertia element connected with said supporting member, an electro-magnet having its armature pivoted on an axis coincident with the axis of said supporting member and connected with said supporting member, a friction member interposed between and having frictional connection with said armature and said supporting member, means for interrupting the movement of said friction member before said armature and said supporting member have completed their movement, and electrical connections between said electro-magnet and said circuit breaker and closer to cause said magnet to be energized when said supporting member is moved in one direction and to be deenergized when said supporting member is moved in the other direction.
  4. In a device of the character described, a pivoted supporting member, a circuit breaker and closer carried by said supporting member, an inertia element connected with said supporting member, an electro-magnet having an armature pivoted on an axis coincident with the axis of said supporting member and connected with said supporting member, a plate movably mounted about the axis of said armature and having means to limit its movement in either direction, a frictional element carried by said supporting member and bearing against said plate to cause said plate to move with said supporting member but to permit the latter to have movement with relation to said plate, and electrical connections between said circuit breaker and closer and said electro-magnet to cause the latter to be energized when said supporting member is moved in one direction and to be deenergized when said supporting member is moved in the other direction.
  5. In a device of the character described, a pivoted supporting member movable in one direction by gravity and having at one end thereof a toothed rack, a rotatable inertia element, a pinion connected with said inertia element and meshing with said rack, a circuit breaker and closer carried by said supporting member, an electro-magnet having its armature operatively connected with said supporting member to move the latter in the other direction, and electrical connections between said circuit breaker and closer and said electro-magnet to cause the latter to be energized when said supporting member approaches the limit of its movement by gravity and to be deenergized when said supporting member approaches the limit of its movement in the other direction.
  6. In a device of the character described, a circuit breaker and closer mounted for tilting movement and arranged to be moved in one direction by gravity, an electrically operated device to move said circuit breaker and closer in the opposite direction and connected in circuit therewith, said circuit breaker and closer being arranged to close the circuit through said electrically operated device before the gravity movement of said circuit breaker and closer has been completed, and an inertia element connected with said circuit breaker and closer independently of the actuating connection between said circuit breaker and closer and said electrically operated device and arranged to retard the initial movement thereof by gravity and to resist the action of said electrically operated device thereon after said circuit has been closed.
  7. In a device of the character described, a circuit breaker and closer mounted for tilting movement and arranged to be moved in one direction by gravity, an electrically operated device to move said circuit breaker and closer in the other direction and connected in circuit therewith, a freely rotatable inertia element, and means separate from the actuating connection between said circuit breaker and closer and said electrically operated device for connecting said inertia element with said circuit breaker and closer for movement in unison and to cause said inertia element to control the movements of said circuit breaker and closer when the circuit for said electrically operated device has been broken.
  8. In a device of the character described, a circuit breaker and closer mounted for tilting movement and arranged to be moved by gravity in a direction to close the same, an electrically operated device to move said circuit breaker and closer in a direction to open the same and connected in circuit therewith, a freely rotatable in-

- ertia element connected with said circuit breaker and closer independently of the actuating connection between said circuit breaker and closer and said electrically operated device to impart further movement thereto after said circuit has been opened and to retard the initial movement thereof in the direction to close said circuit.
9. In a device of the character described, a circuit breaker and closer mounted for tilting movement and arranged to be moved in one direction by gravity, an electrically operated device to move said circuit breaker and closer in the other direction and connected in circuit therewith, and an inertia wheel connected with said circuit breaker and closer independently of the actuating connection between said circuit breaker and closer and said electrically operated device to so control the movements thereof that said circuit breaker and closer will move at a substantially uniform rate of speed in both directions.
10. In a device of the character described, a circuit breaker and closer movable as a unit to cause the circuit to be opened and closed, a pivoted support for said circuit breaker and closer having a toothed rack, an electro-magnet connected in circuit with said circuit breaker and closer, a rotatory armature for said magnet connected with said circuit breaker and closer at the axis thereof, an inertia wheel, and a pinion connected with said inertia wheel and meshing with said toothed rack.
11. In a device of the character described, a circuit breaker and closer movable as a unit to cause the circuit to be opened and closed, a pivoted support for said circuit breaker and closer having a toothed rack, an electro-magnet connected in circuit with said circuit breaker and closer, a rotatory armature for said magnet connected with said circuit breaker and closer at the axis thereof, to move the same in one direction, an adjustable weight connected with said circuit breaker and closer to move the same in the other direction, an inertia wheel, and a pinion connected with said inertia wheel and meshing with said rack.
12. In a device of the character described, a circuit breaker and closer mounted for tilting movement and arranged to be moved in one direction by gravity, and an inertia element connected with said circuit breaker and closer and arranged to retard the initial movement thereof by gravity, an electrically operated device connected in circuit with said circuit breaker and closer and having means operating independently of said inertia element to move said circuit breaker and closer in the opposite direction, and power absorbing means to limit the movement of said inertia element.
13. In a device of the character described, a circuit breaker and closer mounted for tilting movement and arranged to be moved in one direction by gravity, and an inertia element connected with said circuit breaker and closer and arranged to retard the initial movement thereof in both directions, and an electrically operated device connected in circuit with said circuit breaker and closer and having means operating independently of said inertia element to move said circuit breaker and closer in the opposite direction.
14. In a device of the character described, a pivoted supporting member, a circuit breaker and closer supported by said member and adapted to be opened and closed by the pivotal movement thereof, an electro-magnet having an armature connected with said supporting member to impart movement thereto in one direction, electrical connections between said circuit breaker and closer and said electro-magnet to cause the latter to be deenergized when said circuit breaker and closer is opened by the movement of said supporting member in one direction and to cause said electro-magnet to be energized when said circuit breaker and closer is closed by the movement of said supporting member in the other direction, and an inertia wheel operatively connected with said supporting member for movement in both directions therewith.
15. In a device of the character described, a switch mounted for movement as a whole about a fixed axis, an electro-magnet connected in circuit with said switch, a rotary armature for said magnet connected with said switch at the axis thereof, an inertia wheel, and means for operatively connecting said inertia wheel with said switch.
16. In a device of the character described, a pivoted supporting member, a mercury tube switch mounted on said supporting member for movement therewith, an electro-magnet connected in circuit with said switch, a rotary armature for said magnet separate from said supporting member and connected therewith at the axis thereof, an inertia wheel, and means for operatively connecting said inertia wheel with said supporting member.
17. In a device of the character described, an oscillatory member, power means for imparting oscillatory movement to said member, and power absorbing and dissipating means for limiting the excess of said oscillatory movement.
18. In a device of the character described, an oscillatory member, power means for intermittently imparting energy to said member to cause oscillatory movement thereof, and energy absorbing and dissipating means to limit the amplitude of said movement.
19. In a device of the character described, an oscillatory member, power means for imparting oscillatory movement to said member, and frictional power absorbing means for limiting the amplitude of the oscillations of said member.
20. In a device of the character described, an oscillatory member, electrical means for imparting an oscillatory movement to said member, means controlled by said member to intermittently energize said electrical means, and power absorbing means to limit the amplitude of the oscillations of said member.
21. In a device of the character described, an oscillatory inertia element, a pivoted member connected with said oscillatory member for movement therewith, a magnet acting on said pivoted member to impart movement to said inertia element, means connected with said pivoted member to intermittently energize said magnet, and frictional means acting on said pivoted member to limit the amplitude of the oscillations of said inertia element.
